UNITED STATES PATENT OFFICE

JOE BENTON TURMAN, OF LOS ANGELES, CALIFORNIA, ASSIGNOR OF TWENTY-FOUR PER CENT TO WILLIAM I. GILBERT, TWENTY-FOUR PER CENT TO WILLIAM I. GILBERT, JR., TWENTY-TWO PER CENT TO FRED A. WEST, FOUR PER CENT TO JESS E. MORRIS, TWENTY PER CENT TO AILEEN TURMAN, TWO PER CENT TO HOSEA B. TURMAN, JR., TWO PER CENT TO LEWIS F. TURMAN, AND TWO PER CENT TO JOHN R. BARRICK, ALL OF LOS ANGELES, CALIFORNIA

BRAKING APPARATUS

Application filed July 10, 1931. Serial No. 550,008.

This invention relates generally to fluid operated braking apparatus, and the principal object of the present invention is to provide an apparatus of the character referred to which will operate positively and efficiently under all working conditions.

Another object is to provide an apparatus so constructed that gradual or sudden braking action may be secured thereby without subjecting the same to undue strains on the working parts.

A further object is to provide an apparatus of simple and efficient construction which may be readily applied to the drive shaft of a motor vehicle.

Briefly stated, the invention consists of a housing through which passes a shaft adapted to be connected to the mechanism to which the braking apparatus is employed. A pair of opposed cylinders extend from the housing in which pistons operate against a quantity of liquid carried in the cylinders and in a valve controlled by-pass between the cylinders. The pistons are connected to a yoke in which is reciprocably mounted a block in which turns an eccentric keyed to the shaft. During rotation of the shaft, the pistons reciprocate and induce a circulation of liquid to-and-fro through the by-pass. By closing said valve, such circulation is retarded or entirely stopped with corresponding braking effect upon said shaft. The by-pass and cylinders are supplied with liquid from a storage tank which also feeds liquid to the interior of the housing for lubricating the yoke, block and eccentric.

Other objects and advantages will be apparent from the following description, reference being had to the accompanying drawings, in which—

Fig. 1 is a vertical section taken through a motor vehicle chassis with the improved braking apparatus installed thereon, the view being taken substantially on line 1—1 of Fig. 2.

Fig. 2 is a fragmentary top plan view of Fig. 1.

Fig. 3 is a cross section taken on line 3—3 of Fig. 2.

Fig. 4 is an enlarged vertical section of 50 the braking apparatus taken on line 4—4 of Fig. 2.

Fig. 5 is a horizontal section taken on line 5—5 of Fig. 4.

Fig. 6 is a detail section taken through one 55 of the pistons and cylinders of the braking apparatus.

Referring more specifically to the drawings, 10 designates a motor vehicle chassis comprising the usual frame channels 11, engine 12, and drive shaft 14.

The improved braking apparatus generally designated at 16 is interconnected with the drive shaft, and serves to apply braking action to the rear wheels of the vehicle 65 in a manner more fully hereinafter described.

Referring to Figs. 4 and 5, the braking apparatus consists of a pair of oppositely disposed cylinders 22, which projecting from the end walls 23 of a housing 24, and extending through bearing 26 carried by the side walls 28 of the housing is a short shaft 30 connected to the drive shaft 14 by couplings 31.

Keyed or otherwise secured to shaft 30 is 75 an eccentric 32 which turns in an opening formed in a block 34 vertically reciprocable in a yoke 35 which in turn is horizontally reciprocable between guide members 36 carried by the top and bottom walls 38 of the 80 housing. Block 34 is held against shifting on the eccentric by guide pins 39 projecting from the upper and lower members 40 of the yoke into openings 41 formed in the block.

Projecting from the yoke into the cylinders 85 22 are oppositely disposed pistons or plungers 42 which reciprocate therein (during rotation of the shaft) and induce a circulation of fluid, preferably oil, back and forth through a by-pass pipe 43 communicating with the cylinder 90 45.

ders through ducts 44 formed in the outer ends. The pipe 43 has flanged ends 45 which engage and are connected by screws or the like 46 to companion flanges 47 formed on the cylinders.

Disposed in the by-pass pipe 43 is a rotary valve 48 having a port 49 formed therein normally held in open position as shown in Fig. 4.

10 Valve 48 serves to restrict or stop circulation of oil through the by-pass when turned out of register therewith, and is interconnected with the usual brake pedal indicated at P in Figs. 1 and 2 as follows:

15 Secured to the stem 50 of valve 48 is a bevel gear 51 which meshes with a gear 52 secured to a rock shaft 53 mounted in bearings 54 secured to a cross member 55 extending between the frame channels 11.

20 The opposite ends of a link 56 are connected by pins 57 to arms 58 and 59 secured to the rock shaft and brake pedal shaft 60, respectively. It will be readily seen that valve 48 may be partially or fully closed by depressing the brake pedal.

25 During closing of valve 48, circulation of the oil is retarded or entirely stopped with a consequent braking effect on the drive shaft through the parts above described.

30 In order to prevent undue strains on the working parts of said apparatus (during application), a check valve 62 and a coil spring 63 are mounted in a recess 64 formed in the body portion 65 of each piston (see Fig. 6).

35 The springs encircle the check valves 62 and normally hold them seated through engagement with flanges 75 formed thereon.

When seated, the tapered points 66 of said valves close ports 68 formed in plugs 70 screw

40 threaded into sleeves 71 which in turn are threadedly connected to the body portions of the pistons. The pistons being constructed as above described in order that the valves and springs may be assembled therein, or the

45 springs interchanged when required.

Should excessive hydraulic pressure be developed in the cylinders during partial or complete closing of valve 48, said check valves will be unseated during outward movement of each piston. Oil in the cylinders will then pass through the ports 68, openings 72 in the flanges 67, and ducts 73 formed in the body portions of the pistons into the interior of the housings.

50 It will be noted that springs 63 should be of sufficient tension to hold the check valves seated, yet permit them to open according to the weight or load of the vehicle to which the apparatus is applied.

55 In order to keep the cylinders 22 and the by-pass 18 continuously filled with oil, and prevent admission of air thereinto, a small storage tank 74 is provided in an elevated position, and is connected by means of a pipe 75

60 with one of the cylinders 22 whereby with the

aid of gravity and suction created by the piston such oil as may be required will be supplied to said cylinder upon each stroke. For lubricating the yoke, block, and eccentric sufficient oil will leak past the piston 41 into the housing 24, and rise to a level such as shown. A pump including a plunger 78 connected to the yoke, and slidably mounted in a bore 77 formed in one of the end walls 23 of said housing serves to return any excess oil accumulating in the housing back to the storage tank. Excess oil accumulating in the housing enters the bore 77 through a duct 76, and is forced therefrom through a pipe 79 back into the storage tank during outward movement of said plunger. A check valve 80 is interposed in pipe 75 in order to prevent return of the oil to the tank, and a check valve 81 in pipe 79 prevents it from returning to the casing on inward movement of the plunger.

65 The braking apparatus is adapted to be cushioned or protected against road shocks or vibratory movement of the drive shaft about the universal joint. This is accomplished by shock absorbing springs 82 arranged as follows:

70 Parallel channel irons 84 extend between and are connected to the cross member 55 and another member 85 which is also secured to side channels 11 of the frame. Guide rods 85 extend between the flanges of channels 84 and through openings 88 formed in lugs 90 projecting from the cylinders 22. The shock absorbing springs encircle the rods between the lugs and flanges of said channels, and are of sufficient tension to hold the housing in its proper position, but yield sufficiently to prevent undue strains thereon caused by road shocks.

75 From the foregoing, it will be seen that by closing of valve 48 rotation of shaft 30 and drive shaft 14 may be gradually or quickly stopped as required, the action of which is transmitted through the differential and associated parts (not shown) to the rear wheels of the vehicle.

80 Although the apparatus has been shown and described in connection with a motor vehicle, it will be readily understood that it may be advantageously employed as a brake for other uses, for example, tractors and hoisting apparatus.

I claim:

85 1. A braking apparatus comprising a housing, a shaft extending through said housing, cylinders connected to said housing, pistons movable in said cylinders, a yoke connected to said pistons, eccentric means mounted on said shaft and engaging said yoke, a by-pass connecting said cylinders, a valve disposed in said by-pass, a check valve mounted in each of said pistons and normally closing ports formed therein communicating with the cylinders and housing respectively,

and expansion coil springs urging said valves seated against a predetermined pressure developed in said cylinders and by-pass upon closing of the valve in said by-pass.

- 5 2. A braking apparatus comprising a housing, a shaft extending through said housing, cylinders connected to said housing, pistons movable in said cylinders, a yoke connected to said pistons, eccentric means 70
10 mounted on said shaft and engaging said yoke, a by-pass connecting said cylinders, a control valve disposed in said by-pass, check valves mounted in recesses formed in said pistons, springs engaging said check valves 15 and urging them into engagement with seats and closing ports communicating with the cylinders, said check valves adapted to be unseated and permit passage of fluid through said port and ducts communicating with the 20 housing when an excessive pressure is developed in said cylinders and by-pass upon closing of said control valve.

3. A braking apparatus comprising in combination, a drive shaft, a housing through 25 which said shaft passes, a pair of cylinders connected with said housing, pistons reciprocable in said cylinders, a liquid by-pass between said cylinders, a liquid supply leading to one of said cylinders, a yoke connecting 30 said pistons and disposed in said housing, a block reciprocable in said yoke, an eccentric movable in said block and fixed on said shaft, a portion of said housing constituting a reservoir for liquid to lubricate said yoke and 35 eccentric, a pump connected with said housing and operable by said yoke, said pump being adapted to receive liquid from said reservoir and being connected to said liquid supply to return surplus liquid thereto from said 40 reservoir, and a valve in said by-pass to control movement of liquid therethrough when under influence of said pistons.

4. A braking apparatus comprising in combination, a drive shaft, a housing through 45 which said shaft passes, cylinders connected with the housing, pistons reciprocable in said cylinders, actuating means connecting said pistons with said drive shaft, a liquid by-pass between said cylinders, a liquid supply 50 leading to said cylinders and by-pass, a portion of said housing providing a reservoir for excess oil, a pump for returning excess oil to said liquid supply and operable through said actuating means, and a valve in said by-pass to control liquid movement therethrough.

5. A braking apparatus comprising in combination a drive shaft, a housing through which said shaft passes, cylinders connected 60 with the housing, pistons reciprocable in said cylinders, actuating means connecting said pistons with said drive shaft, a liquid by-pass between said cylinders, a valve interposed in said by-pass for regulating the flow of fluid 65 therethrough, a lubricant storage tank dis-

posed in position above said housing, a pipe line leading from said storage tank and communicating with a port formed in the sidewall of one of said cylinders, a pump for returning excess lubricant leaking past the piston into said housing back to said storage tank and operable through said actuating means, and a pipe line leading from said pump to said storage tank.

In testimony whereof I affix my signature. 75
